UNITED STATES PATENT OFFICE.

LLOYD D. FREELAND, OF CHICAGO, ILLINOIS, ASSIGNOR TO WILLIAM J. H. STRONG, OF BELOIT, WISCONSIN.

MOTOR-DRIVEN FAN.

1,265,189.

Specification of Letters Patent.

Patented May 7, 1918.

Application filed March 27, 1915. Serial No. 17,568.

To all whom it may concern:

Be it known that I, LLOYD D. FREELAND, a citizen of the United States, residing at Chicago, in the county of Cook and State of Illinois, have invented certain new and useful Improvements in Motor-Driven Fans, of which the following is a specification.

This invention relates to ventilating fans of the type in which the fan is directly connected to a small hot-air engine, the engine being driven by means of heat derived from any suitable source, as, for example, a lamp in which alcohol or other liquid fuel is burned. Inasmuch as the power obtainable from such a source is comparatively small, it is essential that friction be reduced to a minimum. It is, therefore, one of the objects of this invention to provide a very light-running mechanism and one which may be conveniently adjusted to take up wear.

Another object of the invention is to provide means whereby the mechanism may be easily and safely started and stopped.

It is also an important object of the invention to provide a protected ventilation for the source of heat and also ventilation of the base of the machine for cooling purposes.

A further object of the invention is to provide an improved end-thrust bearing for the fan shaft.

Another object of the invention is to provide simple and reliable means for quickly and conveniently connecting a lamp or other source of heat to the remainder of the structure and for disconnecting it therefrom.

Another object of the invention is to make the entire structure as strong, simple and compact as possible.

The invention also relates to the further features of improvement hereinafter set forth.

In the accompanying drawings, Figure 1 is a rear elevation of a motor-driven fan embodying the features of my invention, the fan proper being omitted. Fig. 2 is a vertical central sectional view taken in the plane of dotted line 2 of Fig. 1. Fig. 3 is an under-side view of a lamp and the structure in which the lamp is supported. Fig. 4 is an enlarged sectional view taken in the plane of dotted line 4 of Fig. 2. Fig. 5 is a top plan view of a sleeve comprised in the construction. Fig. 6 is a fragmental side view

of the sleeve. Fig. 7 is a view of a roller bearing employed in the construction. Fig. 8 is a section on line 8 of Fig. 2.

The embodiment which has been selected to illustrate the invention comprises a base 1 which is chambered to receive the lamp and a portion of the engine, said base comprising a flange 2 which may be equipped with feet 2^a adapted to rest upon a suitable support. The contracted upper end of the base 1 has an opening 3 therein to receive the lower end of the cylinder 4 of the engine. One or more set screws 5 secure the cylinder to the base. These screws extend into an annular groove in the lower end of the cylinder.

The fan shaft and the guard casing that incloses the fan blades are carried by an approximately spherical casing 6, which casing comprises two substantially similar sections 6^a and 6^b, and a removable cover section 6^c. The casing 6 is provided with an annular base flange 7, which is adapted to fit upon an outwardly extending annular flange 8 upon the upper end of the cylinder 4. The flanges 7 and 8 are secured together by screws 9.

10 is a heater having a closed lower end and an open upper end which communicates with the cylinder 4. The heater 10 may be of any suitable construction. Preferably it consists of a tube having relatively thin walls and formed of metal which is a good conductor of heat. The tube may be connected with the cylinder 4 in any suitable way. Herein I have shown the upper portion of the heater 10 as expanded into locking engagement with an internal annular groove 11 in the cylinder. The heat from a lamp or other source of heat is directed against the lower end of the heater. To conserve the heat and cause the heated air or products of combustion to pass upwardly close to the heater, I provide a sleeve 12 surrounding the lower portion of the heater and extending below the heater, said sleeve providing an annular passage 13 for the heated air or products of combustion. In the upper end of the sleeve 12 are outlet openings 14. After passing out through the openings 14, the hot air or combustion products escape to the atmosphere through openings 15 formed in the upper portion of the base 1.

While the sleeve 12 may be held in place

in any suitable manner, I have herein shown it as secured by the means to be now described: Within the upper portion of the base 1 is a plurality of stop shoulders 16 and below each stop shoulder is a rib 17, the upper end of which rib constitutes a supporting shoulder 18. On the upper end of the sleeve 12 is an outwardly extending flange 19 which is notched at 20 to pass the ribs 17. The flange 19 is adapted to lie in the space between the shoulders 16 and 18. At one side of each notch 20, the flange is of wedging or cam formation. After inserting the sleeve 12 upwardly into the base 15 until the flange 19 stops against the shoulders 16, the sleeve may be given a partial rotation to carry the notches 20 out of register with the ribs 17 and thus place the flange 19 between the pairs of shoulders 16 and 18, the turning movement being continued to the extent permitted by the cam or wedging formation of the flange.

Above the outlet openings 14, the sleeve 12 is closed by suitable means, as for example, an annular partition or diaphragm comprising in this instance two sheet-metal rings 21 with an interposed layer 22 of asbestos or other heat insulation. The rings 21 and layer 22 are clamped between the 30 stop shoulders 16 and a shoulder 23 on the sleeve 12.

Upon the lower end of the sleeve 12 is fixed a guard or extension 24, the lower end of which is extended inwardly to surround a burner, sufficient space being provided around the burner to admit air to support combustion. The guard 24 provides within it a combustion chamber 24a.

The sleeve 12, together with the partition 40 at its upper end and the guard 24 at its lower, thus forms a casing completely inclosing the lower portion of the heater, the air to support combustion being drawn through the inlet opening around the burner, 45 in the lower end of said casing, and the gases of combustion being conveyed away from the heater at the upper end of the casing through the outlet openings 14 therein. By this construction the hot gases of 50 combustion are confined to the lower portion of the heater so that the upper portion thereof adjacent the lower end of the power cylinder is not subject to the action of said hot gases.

55 The source of heat comprises in this instance a lamp consisting of a flat circular font 25, and a burner 26 located centrally of the font. The lamp is arranged to be supported with the upper side of the font in 60 contact with a plurality of lugs 27 formed upon the inner surface of the base 1. The means for thus supporting the lamp comprises, in the present embodiment, two approximately semi-circular arms 28 pivoted 65 to the base 1 and adapted to embrace the

font. The arms 28 may be pivotally connected to the base in any suitable manner. Herein I have shown each arm 28 as provided with a perforation to receive a stud 29 cast integral with the base 1, a plate 30 being arranged to underlie the studs and thus retain the arms upon the stud. The plate 30 is secured in place by means of a screw 31. The opposite ends of the arms 28 are provided with fingerpieces 32 which project upwardly through openings in the base. As the arms 28 extend past each other, they may be moved away from each other to release the lamp by pressing the fingerpieces 32 toward each other. A tension-spring 33 normally holds the arms 28 in the position shown in Fig. 3. 28a (Fig. 3) are pins or the like set in the base flange 2 and serving to support the arms 28.

The periphery of the font 25 is beveled as at 34 for two reasons, namely, to provide space for the upward flow of air, and in order that when the base 1 is placed upon the lamp, the arms 28 shall be forced apart to pass the plane of the greatest diameter of the font. The lower portion of the periphery of the font is beveled in the opposite direction to enable the arms 28 to force the font upwardly into contact with the stop shoulders 27.

An annular series of air inlet openings 35 are provided in the lower portion of the base 1 to admit air to support combustion and to keep the base and the font cool.

The mechanism of the engine comprises a power piston 36 arranged to operate within the engine cylinder 4, and a transfer piston 37 which is reciprocable within the heater 10. The transfer piston 37 serves to move the heated air from the heater to the engine cylinder and back in the well known manner. The transfer piston is attached to a piston-rod 38 which passes slidably through a guide-opening 39 in the power piston 36.

The fan shaft 40 is provided with two 110 cranks 41 and 42. The crank 41 for the transfer piston has a greater throw than the crank 42 for the power piston and is set 90° in advance of the crank 42. In order to reduce friction to the minimum, the shaft 115 40 is supported in two roller bearings, which bearings are preferably constructed in the following described manner. In Fig. 4, 43 is a split ring secured to the casing 6 by any suitable means such as two screws 44. The 120 ends of the ring 43 are connected by means of a screw 45. 45a is a lock nut. Projecting inwardly from the ring 43 is a plurality of forks 46 in which rollers 47 are rotatably supported. Two such roller bearings are 125 provided, one for each end portion of the fan shaft. The rings 43 may be contracted to adjust the rollers to the shaft, both initially and to take up wear, by operating the screws 45.

To the power piston 36 is pivoted a connecting rod 48 and to the piston-rod 38 is pivoted a connecting rod 49. These connecting rods engage the cranks 41 and 42 by means of roller bearings 50 and 51. The connecting rods 48 and 49 are integral or otherwise secured to the split rings of their respective roller bearings.

A counterweight 52 may be attached to the shaft 40 to balance the moving parts. One end 52^a of the hub or attaching portion of the counterbalance is arranged adjacent to the roller bearing for the rear portion of the fan shaft. In operation, the thrust of the fan places said hub in contact with the rollers 47 of said roller bearing, the thrust of the fan being thus borne by the rolling elements 47 and 52^a.

The fan blades 53 may be of any suitable character and may be attached to the shaft 40 in any preferred manner. The guard 54 may be of any ordinary construction and may be supported from the forward end of the casing 6 in any desired way.

25 A starting and stopping projection 55 may be affixed to the extended rear end of the shaft 40. Said projection is preferably cylindrical and smooth so that it may be conveniently and safely grasped in manually starting and stopping the rotation of the shaft. If desired, the projection 55 may be grooved as at 55^a to serve as a pulley. The forward end of the projection 55 may extend into proper relation to the rear roller bearing for the shaft so as to limit longitudinal movement of the shaft in one direction.

In practice, after the lamp has been filled and lighted, the base 1 is placed upon the lamp, the arms 28 yielding to pass the plane 40 of the greatest diameter of the font and thereafter approaching each other to support the font in contact with the stop shoulders 27. The air is heated in the heater 10 by the flame, and the rotation of the shaft 40 having been started by manually turning the projection 55, the heated air is transferred from the hot end of the heater 10 to the engine cylinder 4 by the transfer piston 37, and is there cooled by radiation and expansion. Upon the completion of the upward stroke of the power piston 36, atmospheric pressure causes the return or downward stroke of the piston. The heat and products of combustion are caused to pass upwardly 55 around the heater 10 by the sleeve 12. The insulation 22, the openings 15 and the character of the walls of the heater 10 prevent heat from being conducted or radiated to the engine cylinder 4 to an excessive extent. 60 The engine cylinder is ribbed or otherwise suitably adapted to radiate heat.

When it is desired to stop temporarily the operation of the fan, the projection 55 is grasped; and if it is desired to put out the flame of the lamp, the finger pieces 32 are

pressed toward each other to release the lamp, the base 1 raised off the lamp, the flame extinguished and the base replaced upon the lamp.

The multiplicity of openings 14 and 15 causes the hot air and products of combustion to be discharged in a diffused manner. These openings being below the fan, the hot air and products of combustion are not caught by the fan and driven along with the air current, as would be the case if the outlet or outlets were higher.

The upward flow of air between the base and the heater 10 serves to keep the base sufficiently cool so that the base may be touched or lifted without danger of burning the hand.

The sleeve 12 and the guard 24 serve to protect the flame against drafts tending to extinguish the flame.

85 The guard 24 serves to intercept radiant heat and thus assists to protect the font 25 against overheating.

The partition formed of the rings 21 and 22 serves to hold the heater 10 in central 90 relation to the base and the lamp.

The screws 5 need not be driven tightly against the cylinder 4, but may be left sufficiently loose so that the cylinder may be turned in order to face the fan in the desired direction, the partition 21, 22 permitting the heater 10 to turn with the cylinder.

95 While I have described the present embodiment of my invention with considerable particularity, it will be understood that the invention is not restricted to the construction and arrangement shown, and that various changes may be made without departing from the spirit and scope of the invention as set forth in the appended claims.

100 The roller bearings herein disclosed are claimed in my divisional application Serial No. 122,945, filed August 6, 1916.

I claim as my invention:

1. In combination, a base, a power cylinder extending upwardly and a heater extending downwardly from the upper end of the base and in axial alinement with the power cylinder, a casing surrounding the lower portion of the heater and having laterally extending means engaging with the base whereby the casing is supported by the base, and a burner extending into the casing below the heater, there being an air inlet opening in the lower end of said casing around said burner and a plurality of outlet openings near the upper end of the casing arranged to convey the hot gases of combustion away from the heater at a point substantially midway between the ends of 115 the heater.

120 2. In combination, a base, an engine cylinder supported by the base, a heater axially alined with and communicating with the cylinder, a source of heat below the 130

- heater, a tubular structure surrounding the heater and extending below the heater, said structure being supported by the base, an annular air space being provided between the tubular structure and the heater, and an air space being provided between the tubular structure and the base, the upper portion of said tubular structure having ventilating openings, and the lower portion of the tubular structure being contracted to protect the source of heat from radiant heat, means for closing the upper end of the annular air space, another annular air space being provided between the upper portion of the heater and the base, the base having ventilating openings that communicate with the last mentioned air space, the base also having ventilating openings that communicate with the second mentioned air space.
3. In combination, a base, an engine cylinder secured to and extending upwardly from the base, a heater alined with and extending downwardly from the cylinder, a source of heat below the heater, a sleeve within the base and surrounding the heater, the upper portion of the sleeve having ventilating openings, an annular non-conducting partition at the upper end of the sleeve, an air space being provided around the heater above the partition, and an air space being provided between the sleeve and the base, the upper portion of the base having outlet openings that communicate with both of said spaces.
4. In combination, a base, an engine cylinder secured to and extending upwardly from the base, a heater alined with the cylinder, the upper end of the heater and the upper end of the base being in approximately the same horizontal plane, the heater being composed wholly of relatively thin metal, a source of heat below the heater and within the base, and a partition in the base located approximately midway of the length of the heater, the base having ventilating openings above and below said partition.
5. In combination, an engine cylinder, a heater alined with and communicating with said cylinder, a source of heat below the heater, a sleeve surrounding and extending below the heater, said sleeve having means adjacent to its upper end for the escape of

products of combustion, and non-conducting means for closing the upper end of the sleeve.

6. In combination, a base, an engine cylinder secured to and extending upwardly from said base, a heater alined with and extending downwardly from said cylinder, a source of heat below the heater, a sleeve within and attached to the base, said sleeve surrounding and extending below the heater, said sleeve having means adjacent to its upper end for the escape of products of combustion, and non-conducting means for closing the upper end of the sleeve, an annular air space being provided between the sleeve and the base, the upper end of the base having outlet openings, and the lower portion of the base having air inlet openings.

7. In combination, a base having pairs of opposed shoulders therein, a heater supported by said base, and a sleeve surrounding the heater, said sleeve having a flange adapted to lie between the pairs of shoulders, said flange being notched to permit the flange to pass certain of said shoulders.

8. In combination, a base having a plurality of stop shoulders therein, a rib below each stop shoulder, the upper end of each rib providing a supporting shoulder, a heater supported by said base, and a sleeve surrounding the heater, said sleeve having a flange adapted to lie between the pairs of stop shoulders and supporting shoulders, said flange being notched to permit the flange to pass said ribs.

9. In combination, a base having an opening in its upper end, an engine cylinder having its lower end secured in said opening, a heater secured to the engine cylinder, an approximately spherical casing secured to the engine cylinder, a crank shaft supported within and by said casing, a power piston in the engine cylinder, a transfer piston in the heater, and operating connections between the crank shaft and said pistons.

In testimony whereof, I hereunto set my hand in the presence of two witnesses.

LLOYD D. FREELAND.
